(57) **CLAIM**

The ornamental design for a shoe upper, substantially as shown and described.

DESCRIPTION

FIG. 1 is a perspective view of a shoe upper, showing my new design.

FIG. 2 is a front view thereof.

FIG. 3 is a rear view thereof.

FIG. 4 is a right side view thereof.

FIG. 5 is a left side view thereof; and,

FIG. 6 is a top view thereof.

The broken lines in FIGS. 1 through 6 are for environmental purposes only, and form no part of the claimed design.

1 Claim, 6 Drawing Sheets

FIG. 2

FIG. 3

FIG. 4

FIG. 5

FIG. 6
